[57] CLAIM

The ornamental design for roller skate brake, as shown
and described.

DESCRIPTION

FIG. 1 is a left front perspective view of a roller skate
brake showing our new design;
FIG. 2 is a front elevational view thereof;
FIG. 3 is a right side elevational view thereof, the side
opposite being a mirror image;
FIG. 4 is a top plan view thereof;
FIG. 5 is a bottom plan view thereof; and
FIG. 6 is a rear elevational view thereof.
